UNITED STATES PATENT OFFICE.

OSCAR C. MOON, OF CONNELLSVILLE, PENNSYLVANIA, ASSIGNOR OF
ONE-HALF TO AUGUST STICKEL, JR., OF CONNELLSVILLE, PENN-
SYLVANIA.

LUBRICATING-AXLE.

SPECIFICATION forming part of Letters Patent No. 792,838, dated June 20, 1905.

Application filed November 25, 1904. Serial No. 234,273.

To all whom it may concern:

Be it known that I, OSCAR C. MOON, a citizen of the United States, residing at Connellsville, in the county of Fayette and State of Pennsylvania, have invented a new and useful Lubricating-Axle, of which the following is a specification.

The invention relates to improvements in lubricating-axles.

10 The object of the present invention is to improve the construction of lubricating-axles for carriages, wagons, and analogous vehicles, and to increase the strength, durability, and efficiency of such devices, and to provide a 15 simple and inexpensive lubricating-axle adapted to enable either oil or grease to be employed as a lubricant and capable of positively feeding the same to the spindle and of effectually preventing the lubricant from leaking or otherwise wasting.

20 A further object of the invention is to provide a lubricating-axle of this character which may be quickly operated for feeding a quantity of lubricant to the spindle and which will 25 not be materially weakened by the passages for conducting the lubricant to the spindle.

Another object of the invention is to provide means for preventing the operating device from being affected by the jar and vibration incident to the motion of a vehicle, so 30 that there will be no liability of the parts becoming lost or the lubricant being accidentally fed to the axle.

With these and other objects in view the invention consists in the construction and novel combination and arrangement of parts hereinafter fully described, illustrated in the accompanying drawings, and pointed out in the claims hereto appended.

40 In the drawings, Figure 1 is a side elevation of one end of a front lubricating-axle provided with a device constructed in accordance with this invention. Fig. 2 is a longitudinal sectional view of a portion of the same.

45 Fig. 3 is a transverse sectional view on the line 3-3 of Fig. 2. Fig. 4 is an elevation of a portion of a rear lubricating-axle. Fig. 5 is a detail view of the engaging end of the locking-spring.

Like numerals of reference designate corresponding parts in all the figures of the drawings.

1 designates an axle provided with a longitudinal bore or passage 2, extending outward from the bottom of the axle to a point a short 5 distance beyond the inner end of the spindle 3 and having an outer vertical branch or passage 4 communicating with the groove 5, which is of the usual construction and which extends longitudinally of the upper face of the spindle for holding a quantity of the lubricant. The axle is provided at the inner end of the longitudinal passage 2 with a vertical bore or passage 6, extending to the upper face of the body of the axle and communicating with a vertical opening of the axle bed or tree 7. The axle bed or tree 7 is provided at its opening with a metallic lining or tube 8, which preferably extends slightly into the upper end of the bore or passage 6 of the body of the axle to provide a tight joint for preventing any escape of the lubricant. The passages are bored into the axle before the spindle is welded to the body, and as the passages for feeding the lubricant are formed in 75 the body portion of the axle at the collar or enlargement of the spindle and extend only a short distance along the latter the axle is not materially weakened and will last as long as an ordinary axle.

80 The tube or lining 8 may be threaded for engaging the axle-bed, or it may be secured in the opening thereof in any other desired manner, and its upper end receives a depending nipple 9 of an oil-cup 10, which is mounted 85 upon the axle, as clearly shown in Fig. 1 of the drawings. The cup for the reception of the oil or other lubricant is provided with integral clips 11, composed of front and rear sides arranged at the front and rear faces of the axle 1 and connected at the lower face thereof by clip-plates 12. The lower ends 13 of the sides of the clips are threaded for the reception of nuts 14, which engage the clip-plates in the usual manner. In Figs. 1 to 3, 90 inclusive, of the drawings the cup is shown applied to a front axle and is provided with a pair of clips the front sides of which are en-

larged and provided with openings to form ears 15. The ears 15 are adapted to constitute a portion or member of a thill-coupling and are designed to receive a pivot for connecting a shaft or thill iron to them in the ordinary manner. In Fig. 4 of the drawings is illustrated an oil-cup having a single clip 16 for engaging a rear axle 17. By this construction the oil-cup is applied to an axle by the fastening means usually employed for securing the body of the axle to the axle bed or tree and additional fastening devices are dispensed with.

The lower face of the bottom of the cup is concaved to conform to the configuration of the upper face of the axle bed or tree, and the depending nipple, which projects from the concaved face, may be either formed integral with the oil-cup or consist of a tube threaded into an opening of the bottom of the oil-cup. The nipple projects into the opening or passage of the axle-bed and communicates with and discharges the lubricant into the feed or supply passage of the axle. The oil-cup is provided with exterior screw-threads 18, and it is engaged by an interiorly-threaded cap 19, the screw-threads being sufficiently fine to afford an air-tight joint or connection when the parts are assembled to prevent the lubricant from leaking through the outlet of the bottom. The cap is provided with an exteriorly-milled flange 20 for enabling it to be readily rotated, and it is provided with a cylindrical block or plunger 21, fitting snugly within the bottom of the oil-cup and adapted when the cap is screwed downward to force a quantity of the lubricant out of the oil-cup through the feed-passage of the axle for lubricating the spindle. The cylindrical block or plunger is connected to the top of the cap by a screw 22, which is suitably secured in the threaded aperture of the upper end of the block or plunger and which engages a socket of the top of the cap. The cap is provided with a stud or projection 23, extending from the center of the top of the cap and having a portion of the socket formed in it. It increases the thickness of the cap at this point for enabling a socket of the desired length to be provided, and it is adapted also to be engaged by a locking-spring 24 to prevent the cap from accidentally rotating, as hereinafter explained. The block or plunger is provided at its lower face with indentations or sockets 25, adapted to receive a suitable tool or instrument for enabling it to be rotated for assembling or separating the parts.

The stud or lug 23 is provided at its upper end with a groove 26, adapted to be engaged by a rib or flange 27 of the locking-spring. The groove is triangular in cross-section, and the rib or flange of the locking-spring con-

forms to the configuration of the groove; but any other form of groove and rib or flange may be employed, as will be readily understood. The rib or flange preferably consists of a head or piece having a shank piercing the free end of the spring and suitably secured to the same.

The locking-spring is secured at its inner end to the axle by one of the intermediate clips 28 thereof, and the spring, which is adapted to lock the cap against rotation, is of sufficient length to prevent mud or other accumulation from freezing on the axle and interfering with the operation of the device.

Having thus fully described my invention, what I claim as new, and desire to secure by Letters Patent, is—

1. In a device of the class described, the combination with an axle and an axle-bed having feed-passages, of a cup having an outlet communicating with the said passages, said cup being provided with depending sides or arms arranged in pairs at the front and back of the axle and receiving the same and the axle-bed, the front sides or arms being spaced apart to receive a thill-iron and enlarged and provided with openings to form one member of a thill-coupling, clip-plates connecting the sides or arms, and nuts mounted on the sides or arms and engaging the clip-plates.

2. In a device of the class described, the combination with an axle having a feed-passage, of a cup mounted on the axle and having an outlet communicating with the said passage, a threaded cap engaging the cup, and a locking-spring secured to the axle and provided with means for engaging the cap for holding the same against rotation.

3. In a device of the class described, the combination with an axle having a feed-passage, of a threaded lubricant-cup, a threaded cap engaging the cup, and a spring disposed longitudinally of the axle and secured at one end to the same and provided at its other end with means for engaging the cap for holding the latter against rotation.

4. In a device of the class described, the combination of an axle having a lubricant-passage, a cup having an outlet communicating with the passage and provided with threads, a threaded cap engaging the cup and provided with a projecting lug having a groove, and a spring mounted on the axle and provided with a rib for engaging the groove to lock the cap against rotation.

In testimony that I claim the foregoing as my own I have hereto affixed my signature in the presence of two witnesses.

OSCAR C. MOON.
